D/6755

UNITED STATES PATENT OFFICE.

GEORGE W. PRALL, OF LAMBERTVILLE, NEW JERSEY, ASSIGNOR TO THE
LAMBERTVILLE RUBBER COMPANY, OF SAME PLACE.

DESIGN FOR AN INDIA-RUBBER RATTLE.

SPECIFICATION forming part of Design No. 16,755, dated June 22, 1886.

Application filed May 3, 1886. Serial No. 201,005. Term of patent 14 years.

To all whom it may concern:

Be it known that I, GEORGE W. PRALL, a citizen of the United States, residing at Lambertville, in the county of Hunterdon and State of New Jersey, have invented or produced a new and original Design for India-Rubber Rattles, of which the following is a specification.

This design has for its object to provide a novel and attractive india-rubber rattle for children.

The design is illustrated in the accompanying drawing, in which the figure is a side elevation of the rattle.

Referring to the drawing, the numeral 1 indicates the body, which is campanulate or bell-shaped, with an irregular line, 2, to make it represent the Liberty Bell. The bell-mouth flares outwardly, as at 3, and the bell-body is provided with annular lines 4 both at top and bottom. The stem or handle 5, adjacent to the bell-shaped body, is provided with annular ribs 6, and terminates at its outer end in a

ring, 7, the sides of the stem next the ring bearing waved or scalloped segmental lines 8. 25

The form shown provides a novel, unique, and attractive india-rubber rattle for children.

Having thus described my design, what I claim is— 30

1. The design for an india-rubber rattle, consisting of a campanulate or bell-shaped body and a stem terminating in a ring, substantially as shown and described.

2. The design for an india-rubber rattle, 35 consisting of the representation of the Bell of Liberty and the ornamented stem terminating in a ring, substantially as shown and described.

In testimony whereof I affix my signature in presence of two witnesses.

GEORGE W. PRALL.

Witnesses:

HENRY R. BARBER,
WARREN A. GREENE.
